CLAIM

The ornamental design for a vehicle front upper grille, as shown and described.

DESCRIPTION

FIG. 1 is a top, front, and left side perspective view of a vehicle front upper grille showing our new design;

FIG. 2 is a top, front, and right side perspective view thereof;

FIG. 3 is a top, rear, and left side perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 a is bottom plan view thereof.

The broken lines in the drawings illustrate portions of the vehicle front upper grille that form no part of the claimed design.
